(57) **CLAIM**

The ornamental design for a honeycomb pattern cup, as shown and described.

DESCRIPTION

FIG. 1 is a front, top perspective view of a honeycomb pattern cup, showing my new design;

FIG. 2 is a front view thereof;

FIG. 3 is a back view thereof;

FIG. 4 is a left side view thereof;

FIG. 5 is a right side view thereof;

FIG. 6 is a perspective view of the honeycomb pattern cup in an open position;

FIG. 7 is a front view thereof, in an alternate open position;

FIG. 8 is a top view thereof; and,

FIG. 9 is a bottom view thereof.

All broken lines represent portions of the honeycomb pattern cup that form no part of the claimed subject matter.
